UNITED STATES PATENT OFFICE.

DANA H. BENJAMIN, OF CLEVELAND HEIGHTS, OHIO, ASSIGNOR TO THE AMERICAN LAUNDRY MACHINERY COMPANY, OF CINCINNATI, OHIO, A CORPORATION OF OHIO.

DRYING TUMBLER.

Application filed June 8, 1919. Serial No. 302,748.

To all whom it may concern:

Be it known that I, DANA H. BENJAMIN, a citizen of the United States, residing at Cleveland Heights, in the county of Cuyahoga and State of Ohio, have invented certain new and useful Improvements in Drying Tumblers, of which the following is a specification.

This invention relates to drying tumblers such as are used for drying clothing or wearing apparel in a laundry, or for removing gasoline or other cleaning agents from clothing in a dry cleaning plant.

The object of the invention is to provide a multiple compartment drying tumbler which simultaneously dries a plurality of separate charges of work, and in which heated air is distributed more uniformly and thoroughly through and over the material being dried, so as to increase efficiency.

A further object of the invention is to provide an improved drying tumbler including a rotary drum in which the material to be dried is tumbled, together with means for circulating air from the outside through said drum and also from its center and along its axis outwardly through the drum to thereby improve the drying effects.

Further objects of the invention are in part obvious and in part will appear more in detail hereinafter.

In the drawings, which represent one embodiment of the invention, Fig. 1 is a sectional elevation on the line 1-1, Fig. 2, looking in the direction of the arrows; Fig. 2 is a sectional elevation on the line 2-2, Fig. 1, parts being omitted for simplicity of illustration; Fig. 3 is a detail view looking in the direction of the arrow A, Fig. 1; and Fig. 4 is a broken out plan view.

The tumbler shown in the drawings comprises a suitable outer casing or jacket 1 provided with an inner wall 1^a forming a heating chamber 2 in which are the usual heating coils 3 communicating with a suitable source of heat, such as steam or the like. In said casing is a drying chamber 4 surrounded by a substantially cylindrical wall 5 provided with an opening 6 at its top communicating with a channel or passage 7 coming from the heating chamber 2, and at its bottom having an opening 8 leading to the screening chamber 9 in which are

the usual screens 10 for removing lint and foreign matter carried from the work to said screens by the air current. The screening chamber communicates through an opening 11 and channel 12 with the suction side of a fan or pump 13, which delivers a current of air through a passage 14 extending beneath the heating chamber and having an outlet 15 to the atmosphere. Communication between said passage and the heating chamber is through the opening 16 controlled by a movable door 17. In the upper position of said door, illustrated in dotted lines Fig. 1, communication to the heating chamber is entirely cut off and the entire air current passes out to the atmosphere. In the lower position of said door, shown in full lines, part of the air delivered by the fan 13 flows through the heating chamber and part flows beneath the edge of said door and out through the passage 15, all as more fully described in a prior application of John J. Dewey for drying apparatus, Serial No. 211,531, filed January 12, 1918, to which reference may be had for a more complete description of the general construction of the tumbler.

18 represents a screened inlet from the atmosphere to the screening chamber, and 19 a suitable hinged door providing access to the drying chamber 4 within the cylindrical wall 5.

In said drying chamber is located the tumbling drum having a cylindrical outer wall 20 formed of perforated metal, wire screen, or like foraminous material connected to the two end heads or discs 21. At the center or axis of said drum is a hollow shaft or tube 22 extending at one end through one of the discs 21 into a bearing 23 of the stationary frame. The cavity or space within the tumbling drum is divided into a plurality of compartments 24, three being shown, which compartments lie between the radially extending walls 25 connecting the cylinder 20 and tube 22. These walls may be of any suitable form but are constructed of perforated metal, wire mesh, or foraminous material similar to the cylinder 20. Each compartment is provided with a door 26 affording communication thereto and which doors in turn can be brought into registry with the opening at the door 19 of the outer casing.

At some suitable point on the casing is located a second fan or blower or other circulating device, indicated at 27, the suction side thereof communicating through an opening 28 with the upper end of the heating chamber 2, and the discharge side of said fan communicating through a passage 29 with a hollow tube 30 entering the open end of the tube 22, the opposite end of which tube is closed and rotates in a bearing in the casing similar to bearing 23. Tube 22 is also provided with several series of openings 31, shown as longitudinally extending slots distributed at intervals along the tube, each series of which slots provides communication from the channel 32 in the tube to one of the compartments 23.

The operation of the tumbler will be readily understood. By manipulation of the doors 19 and 26 charges of clothing, wearing apparel or other material to be dried can be readily inserted into or removed from any or all compartments of the drum. The doors being closed the drum is then rotated by any suitable means (not shown) and the fans or blowers started. Air is drawn in through the inlet 18, passes through the screening chamber and is delivered by the fan 13 to the heating chamber, a part of the air passing out through the outlet 15. The heated air in chamber 2 is divided and flows along two separate paths. A part of said air flows through the channel 7 and opening 6 into the outside of the drying chamber and flows across said chamber through the drum and material therein to the outlet 8 where it enters the screening chamber and is again circulated through the tumbler by the fan 13. The second current of air from the heating chamber passes through the fan 27 and is distributed by the hollow tube 22 along the full length of the axis of the drum, so that said heated air is directed immediately upon the material at the center of the drum. This current of air then flows out through the outlet 8 and joins and is circulated again with the remaining air. Consequently, there is a continuous and repeated circulation of air through the machine, a constant inflow of some air through the inlet 18, and a constant discharge of the heavier moisture laden air to the atmosphere. The material being dried is attacked from all sides by heated air and is consequently dried more rapidly.

The construction described prevents the material in the drum from balling up into a solid mass whose interior is not directly attacked by an air current but continually breaks up the material and thoroughly distributes heated air therethrough.

What I claim is:

1. Drying apparatus, comprising a casing provided with a drying chamber, and means for introducing two streams of air into said

chamber, one of said streams entering the drying chamber near its periphery and the other near its center.

2. Drying apparatus, comprising a casing provided with a drying chamber, a rotary foraminous drying drum therein, a perforated hollow shaft for said drum, and means for introducing a stream of air through said hollow shaft to said chamber and for withdrawing it from the periphery of said drum.

3. Drying apparatus, comprising a casing provided with a drying chamber, a rotary drying drum therein, and means for introducing a stream of air to said chamber along the axis of said drum, and means for screening said air and returning it to said chamber.

4. Drying apparatus, comprising a casing, a rotary drying drum therein provided with an axially extending perforated hollow shaft communicating with the chamber in said drum, and means for supplying air through said shaft and withdrawing the same from the periphery of said drum.

5. Drying apparatus, comprising a casing, a rotary drying drum therein provided with an axially extending hollow shaft communicating with the chamber in said drum, means for supplying air to said shaft, and additional means for conducting a separate current of air to the periphery of said drum.

6. Drying apparatus, comprising a casing provided with a drying chamber, a foraminous drying drum therein provided with a perforated hollow shaft and with radial partitions forming a series of compartments, and a door for each compartment.

7. Drying apparatus, comprising a casing provided with a drying chamber, a drying drum therein provided with partitions forming a series of compartments, and means for distributing air along substantially the full axis of the drum to each of said compartments.

8. A drying tumbler, comprising a casing provided with drying and heating chambers, conduits connecting said chambers and entering said drying chamber at different points for conducting separate streams of heated air thereto, and means for returning said air to the heating chamber.

9. A drying tumbler, comprising a casing provided with drying and heating chambers, means for continuously circulating air therethrough, and separate means for conducting a second stream of air from the heating to the drying chamber.

10. Drying apparatus, comprising a casing provided with heating and drying chambers, a rotary drying drum in said drying chamber, means for conducting air from the heating to the drying chambers, and separate means for conducting air from the heating chamber to the drying drum, and means

for returning moist air to the heating chamber.

11. Drying apparatus, comprising a casting provided with heating and drying chambers, a rotary drying drum in said drying chamber, means for conducting air from the heating chamber to the drying chamber, and separate means for conducting air from the heating chamber to the drying drum and 10 for distributing the same along the axis thereof.

12. Drying apparatus, comprising a casting provided with heating and drying chambers, a rotary drying drum in the drying 15 chamber and provided with a perforated hollow shaft, said drum being provided with

radial partitions forming a plurality of compartments, and means at the center of said drum for supplying air from said heating chamber through said hollow shaft to 20 each of said compartments.

13. Drying apparatus, comprising a casting provided with heating and drying chambers, means for conducting air to the heating chamber and for circulating the same 25 through the drying chamber, a rotary drum in said drying chamber provided with a hollow axially extending shaft, and means for conducting air from the heating chamber to said hollow shaft. 30

In testimony whereof I affix my signature.
DANA H. BENJAMIN.
